COIN ACTUATED ELECTRICAL SWITCH

Harold B. Vroom, Hartford, Conn., assignor to
 Veeder-Root Incorporated, Hartford, Conn., a
 corporation of Connecticut

Application October 11, 1946, Serial No. 702,675

6 Claims. (Cl. 194—9)

1

The present invention relates to a coin actuatable electrical switch, and more particularly to a device adapted to temporarily close an electrical circuit when a coin is deposited therein, the same being particularly adapted for use with associated devices such as vending or dispensing machines.

As representative of the many installations to which the present invention relates, reference may be had to vending or dispensing machines of the type in which the machine operates automatically, when a customer deposits a proper coin in a receptacle or control box, to deliver a suitable unit or quantity of merchandise which is purchased by the customer upon the insertion of the proper coin. The function of the device of the present invention is to temporarily close an electrical circuit when the proper coin is deposited therein, thereby initiating the operation of the associated apparatus, for example, an automatic beverage dispensing apparatus, which thereafter automatically dispenses the merchandise purchased.

It is an object of the present invention to provide a device for temporarily closing an electrical circuit of the type which is actuated by dropping a suitable coin therethrough, said device being arranged to be actuated by the weight of the coin and to operate efficiently and in an improved manner.

A more particular object of the invention is to provide such a coin actuated electrical switch device in which the actuated elements are so freely movable as to be readily actuatable by the weight of the coin but which, at the same time, are less susceptible to tampering or accidental actuation, particularly insofar as the device cannot be actuated merely by bumping or shaking the switch supporting elements, this being accomplished without the use of complicated damper mechanisms or strong springs etc. which normally would interfere with the smooth and dependable actuation of the device by a proper coin.

It is another object of the invention to provide a device of the character described which is compact in design and which provides a positive switch action and which, at the same time, is simple to construct with a minimum of movable parts which will function efficiently without breakdown over long periods of time.

Other objects will be in part obvious and in part pointed out more in detail hereinafter.

The invention accordingly consists in the features of construction, combination of elements

2

and arrangement of parts which will be exemplified in the construction hereafter set forth and the scope of the application of which will be indicated in the appended claims.

In the drawing—

Figure 1 is a front view of the assembled device constructed in accordance with the invention;

Fig. 2 is a side view of the same device;

Fig. 3 is a cross sectional view taken along the line 3—3 of Fig. 1; and

Fig. 4 is an enlarged perspective view of one of the electrical contact elements utilized in the device.

Referring to the drawing, the device constructed in accordance with the invention, which is adapted to temporarily close an electrical circuit upon the deposit of a suitable coin, is provided in the embodiment shown with a base or back plate 10 provided with a pair of lugs 11 containing openings 12 by means of which the device may be fastened to a support. For convenience, such support may be a side wall of the vending or dispensing apparatus (not shown) with which the device is to be used.

Fixed to the front of the base plate 10, as, for example, by spot welding, is a front plate 13 having a central, elongated, struck-out portion 14 defining with the back plate 10 an elongated downwardly-extending coin passageway 15 of sufficient size to receive a coin of the denomination desired. As will be apparent from the drawing, the coin is received in said passageway parallel to the front and back plates with the edges of the coin between the sides 8 and 9 of the passageway and will fall by gravity therethrough. The front plate 13 generally conforms to the outline of the back plate 10, extending downwardly at one side thereof to form a V-shaped slot 7 with a foreshortened leg 6. A lip 15A is provided to facilitate the insertion of a coin into the passageway 15.

The electric circuit closing elements of the device are positioned exteriorly of the front plate 13 at substantially the center thereof and are disposed on an insulating member 16 adapted to insulate the elements from the metal front plate 13. These elements comprise two downwardly extending flexible arms 17 and 18 which at their upper ends are sandwiched between insulating members 19, said arms and insulating members being assembled together by a plurality of rivets 20. The central insulating member 19 of the assembly is secured to the front

50 55

plate 13 through insulating member 16 by a plurality of rivets 30.

The flexible arm 17 is in the form of a flexible, flat, elongated strip of metal having a contact point or area 21 at its lower end and having a connecting post or nib 22 adjacent its upper end. The flexible arm 18 has a similar contact point or area 23 adapted to be moved against the contact area 21 of arm 17 when the arms are flexed together, thereby closing an electric circuit. The arm 18 also has a similar connecting post or nib 24 at its upper end.

The lower extremity of the arm 18 is provided with a right angle extension 25 on which is supported at the end thereof a rearwardly disposed arcuate cam surface 26 which is positioned within the coin passageway 15 and spaced from the side 9 thereof. The positioning of the cam surface 26 within the passageway 15 is such that a coin dropped downwardly through the passageway 15 must necessarily encounter said cam surface and move it outwardly from the side 9 thereby moving the switch arm 18 inwardly toward the switch arm 17, thereby closing the electric circuit. The cam surface 26 is spaced from the side 9 of the passageway 15 a proper distance such that a coin passing between the side 9 of the passageway and the cam surface 26 will be guided by the side 9 to insure that the arm 18 will be moved a sufficient distance to cause the electrical circuit to close as described above. In order that the weight of the coin will be sufficient to pivot the switch arm 18 into contact with switch arm 17, it is an advantage of the invention that the spring action of the arm 18 may be made very light without, at the same time, running the risk of having the arm susceptible to being moved to circuit closing position by accidental or deliberate bumping or shaking of the device. The means for accomplishing this will be described more fully hereinafter.

As the arm 18 is pivoted away from the side 9, the coin is permitted to fall through, i.e. to ride off the lower end of the cam surface, from whence it may drop into a suitable receptacle (not shown in the drawing). The cut-off portion of the front plate 13, i.e. the space below the leg 8, permits free movement of the arm 18 including its right angle extension 25 and the cam surface 26 so that there is no interference with the switching action of the device.

For preventing accidental or deliberate closing of the easily flexed switch elements without the deposit of a proper coin, there is pivotally supported intermediate the ends of and between the switch arms 17 and 18 a depending insulating plate 27 which, in the specific embodiment shown, is generally shaped like the sector of a circle, except for a notch 28 in the lower rear portion thereof. The plate 27 is sufficiently light and freely mounted so that it also can be readily pivoted by the weight of a coin. The insulating plate 27 is preferably suspended adjacent its upper apex by a pin 29 supported in the insulating members 19. The arms 17 and 18 are provided with sufficiently large openings 31 through which the pin 29 may extend without making electrical contact therewith.

The switch arms 17 and 18 are adjusted so that in their normal at rest position the insulating plate 27 will freely pass therebetween. The insulating plate 27, by reason of its upper edge 32, provides a camming surface centrally located in the passageway 15 intermediate the sides 8 and 9 thereof. The back plate 10 contains a

slot 33 for receiving the insulating plate 27, the upper edge of said slot acting as a back stop for the insulating plate 27 when the same is pivoted. By reason of the camming surface or edge 32 located within the coin passageway 15, a coin dropped through the passageway 15 must necessarily pivot the insulating plate 27 outwardly from the device to such an extent that the notch 28 clears the contact areas 21 and 23, thus permitting the contact arms 17 and 18 to be flexed together to close the electrical circuit. As the insulating plate never completely leaves the space between the arms 17 and 18, there can be no misalignment of the movable parts so as to cause malfunctioning of the device.

The pivoting action of the insulating plate 27 and the camming of the arm 18 in the direction of the arm 17 are sequential operations, which is to say, the insulating plate 27 is first moved to open position and thereafter the contact points 21 and 23 are brought together. The attempted return of the insulating plate 27 to original position by gravity is prevented so long as the coin is still riding on the cam surface 26 of the arm 18, but as soon as the coin rides off the end of the cam surface 26 and the switch arm 18 returns to original position, the insulating plate 27 readily falls between the contact areas 21 and 23.

By reason of the insulating plate 27, as mentioned heretofore, the switch closing elements may be very lightly biased so that the circuit can be readily closed by the weight of a coin and yet these elements are guarded by the insulating plate 27 so that it is impossible for someone to cause the switch to close in any way except by depositing a coin into the passageway 15. It will be apparent that the movement of the switch arms 17 and 18 and the movement of the insulating plate 27 are at a right angle to each other so that a jar or jolt which is so directed as to pivot the insulating plate 27 from between the switch arms 17 and 18 would be improperly directed to cause the switch arms 17 and 18 to be moved together. Conversely, a force tending to cause the switch arms 17 and 18 to be moved together would be improperly directed for affecting the insulating plate 27. Accordingly, the switch has been made tamper-proof in a relatively simple and easily constructed manner.

The device is positive in action and not susceptible to malfunctioning because the interlocking and circuit closing steps are sequential in operation and all of the actuated elements can be made sufficiently light or lightly biased so as to be readily actuated by the weight of a coin. Moreover, the device is constructed of a relatively few movable parts and is compact in design whereby a device of economical manufacture and great utility is provided.

In light of the above disclosure, it will be apparent that one skilled in the art may modify the device within the scope of the invention, and all such modifications and variations are intended to be included within the scope of the following claims.

I claim as my invention:

1. A coin actuatable electric switch comprising a downwardly extending coin passageway, electric circuit closing means comprising a movable member having a contact surface adapted to be moved into circuit closing position by the weight of a coin, a movable insulating member normally covering said surface and

adapted to be moved away from surface by the weight of a coin, and means on said members extending into said passageway for causing sequential operation of said members by a coin dropped through said passageway.

2. A coin actuatable electric switch comprising a downwardly extending coin passageway, electric circuit closing means comprising a flexible arm having a contact surface and adapted to be flexed into circuit closing position by the weight of a coin, an insulating member pivotally supported for normally covering said contact surface and adapted to be moved away from the contact surface by the weight of a coin, and means on said members extending into said passageway for causing sequential operation of said members by a coin dropped through said passageway.

3. A coin actuatable electrical switch comprising a depending arm having a contact surface for closing an electric circuit, said arm being biased toward circuit open position and being sufficiently lightly biased to be readily moved to circuit closing position by the weight of a coin, and a depending member swingable at substantially a right angle to movement of the arm, said member being biased into position insulating said contact surface and being readily movable to non-insulating position by the weight of a coin, a downwardly extending coin passageway, and means on said arm and insulating member extending into said passageway in spaced relationship to cause sequential actuation of said arm and member when a coin is dropped through said passageway.

4. A coin actuatable electrical switch comprising a downwardly extending coin passageway, electric circuit closing means comprising a flexible arm having an electric contact surface and a cam surface extending into the coin passageway, said arm being normally in circuit open position and sufficiently flexible to permit closing of the circuit by the weight of a coin dropped on said cam surface, a depending insulating member having a cam surface extending into the coin passageway above said first named cam surface,

said insulating member normally covering said electric contact surface and being sufficiently light in weight to be pivoted away from the contact surface by the weight of a coin dropped on its cam surface.

5. A coin actuatable electrical switch comprising a pair of flexible arms normally spaced apart and having areas arranged to form an electrical contact therebetween, a pivotally mounted insulating member depending between said areas, a coin passageway, a cam surface on said insulating member extending into said passageway and arranged to cause the insulating member to pivot from between said areas when a coin is passed through said passageway, and a cam surface on one of said arms extending into said passageway and arranged to cause said arm to be flexed to bring said areas together, said cam surfaces being disposed for sequential actuation by the coin.

6. A coin actuatable electrical switch comprising a coin passageway having vertically disposed sides, a pair of depending flexible arms normally spaced apart and having contacting areas at their lower ends arranged to form an electrical contact therebetween, one of said arms having an extension forming a cam surface within said passageway whereby a coin dropped through said passageway will move said cam surface away from one side of the passageway thereby flexing said arm to bring said contacting areas together, and a pivotally mounted flat insulating member depending between said areas having an inclined edge extending into said passageway above said cam surface and intermediate the sides of the passageway whereby a coin dropped through said passageway will pivot said member outwardly before coming into contact with the first named cam surface, said insulating member having a notched portion adapted to clear the contacting areas when the member is pivoted outwardly by a coin.
